Patented Oct. 31, 1916.

UNITED STATES PATENT OFFICE.

ALFRED LEWIS HARRINGTON, OF RALEIGH, NORTH CAROLINA.

HIGH-TENSION AND TELEPHONE LINE CONSTRUCTION.

1,203,540.

Specification of Letters Patent.

Patented Oct. 31, 1916.

Application filed November 6, 1915. Serial No. 60,171.

To all whom it may concern:

Be it known that I, ALFRED L. HARRINGTON, a citizen of the United States, and a resident of Raleigh, in the county of Wake and State of North Carolina, have invented a new and Improved High-Tension and Telephone Line Construction, of which the following is a full, clear, and exact description.

10 This invention relates to a telephone line construction in connection with high tension transmission lines.

The invention has to deal more particularly with an improved method of transposing the telephone line so as to effectively neutralize the induction effect of the high tension power line, the construction involving a novel arrangement of cross arms and stringing of the wires so that a considerable 20 saving in the cost of material, in time, and expense of erection and maintenance results.

More specifically the object of the invention is to provide an improved telephone line in which the two sides of the circuit 25 are strung in such a manner that each side follows approximately a spiral line which is disposed one hundred and eighty degrees from the other line with relation to an axis passing through the spirals or helices, this 30 arrangement being obtained by disposing the cross arms for the telephone wires forty-five degrees to the vertical or the pole and alternating cross-bars being oppositely inclined, and the wires that are strung on 35 the ends of the cross-arm being crossed between every other pair of cross-arms, with the point of crossing midway between such pairs of cross-arms.

For a more complete understanding of the 40 invention reference is to be had to the following description and claims taken in connection with the accompanying drawing which illustrates one embodiment of the invention and wherein similar characters of 45 reference indicate corresponding parts in all the views.

Figure 1 is a perspective view of the improved telephone line construction; Fig. 2 is a plan view; Fig. 3 is a plan view of a 50 pole, a cross-arm and mounting therefor; Fig. 4 is a side view of the bracket or mounting attached to the pole and supporting a cross-arm; Fig. 5 is a perspective view of the cross-arm bracket or mounting; Fig. 55 6 is a perspective view of a pole, showing

the high tension power wires and telephone wires connected with the cross-arms thereof.

Referring to the drawing, 1 designates the usual line supporting poles which are provided, as shown in Fig. 6, with horizontal cross-arms 2 for high tension power wires 3, and mounted at a lower point on each pole is a cross-arm 4 which is disposed at an angle of forty-five degrees to the axis of the pole so that one end is higher than the other. These arms on alternate poles are, as shown in Fig. 1, oppositely disposed so that each end of every cross-arm 4 will be higher or lower than the corresponding ends of the next cross-arms in either direction 79 therefrom. These cross-arms 4 are rigidly held on the poles 1 by the use of brackets 5. Each bracket comprises a cast plate 6 of square form and having extending from one face corner lugs 7. In the center of the 75 bracket 5 is an opening 8 so that a bolt or equivalent fastening 9^a can pass therethrough. The bolt 9^a serves to fasten the cross-arm 4 to the pole 1, the fastening passing through the cross-arm and being driven 80 or forced into the pole 1. The bracket 5 is so positioned that the corners will lie in vertical and horizontal lines and the cross-arm 4 is of such width as to fit between the lugs 7. The brackets permit of the cross- 85 arms being placed in either of the two angles shown in Fig. 1. The telephone line wires 9 and 10 are fastened to the insulators 11 on the cross-arms 4, and these wires have alternate sections *a* and *a'* crossing each other at the 90 points 12 and 13, and alternate sections *b* and *b'* which are parallel when viewed in plan as shown in Fig. 2, but as the cross-arms are alternately oppositely inclined the corresponding ends of the sections *a* and *a'* 95 and *b* and *b'* are not in the same level. Explained in a general way, each telephone line wire 9 and 10 follows the form approximately of a helix, the axis of which coincides with the centers of the cross-arms 4, and the two lines are disposed one hundred and eighty degrees apart with respect to this axis. The convolutions of the helices are of such length as to extend from a given cross-arm 4 to the fifth cross-arm therefrom. 100 As for instance, a convolution of the wire 10 begins at *c* or the extreme left cross-arm Fig. 2 and ends at *c'*, the extreme right cross-arm, Fig. 2. This method of stringing the telephone line wires is extremely simple, in- 105

expensive and carried on with despatch, and the wires have corresponding portions widely spaced apart and effectively transposed with respect to the high tension power wires.

From the foregoing description taken in connection with the accompanying drawing, the advantages of the construction and method of operation will be readily understood by those skilled in the art to which the invention appertains, and while I have described the principle of operation, together with the structure which I now consider to be the best embodiment thereof, I desire to have it understood that the structure shown is merely illustrative and that such changes may be made when desired as fall within the scope of the appended claims.

On the rear of the bracket 5 are ribs 5^a which engage the pole 1 and prevent the plate from turning on the fastener 9^a as a center.

Having thus described my invention, I claim as new and desire to secure by Letters Patent:

1. In a line construction, the combination of a plurality of poles, members fastened to the poles, and wires supported wholly by the members, the wires being spaced apart at all points and strung helically, with each con-

volution equal to four times the distance between adjacent poles.

2. The combination of telephone line wires, supports therefor including cross-arms arranged at approximately forty-five degrees to the horizontal, and alternate cross-arms being oppositely inclined, the line wires crossing as viewed in plan at points between alternate pairs of cross-arms, the wires being out of contact with each other at all points.

3. In a telephone line construction, the combination of spaced supporting poles, cross-arms fastened thereto and arranged at approximately forty-five degrees to the horizontal, and alternate cross-arms being oppositely inclined, and line wires strung on the cross arms and arranged as helices disposed around a line passing through the centers of the cross-arms, the helices having convolutions of such length as to extend the distance of four consecutive cross-arms.

In testimony whereof I have signed my name to this specification in the presence of two subscribing witnesses.

ALFRED LEWIS HARRINGTON.
